UNITED STATES PATENT OFFICE.

RICKASON STILWELL, OF NEW YORK, N. Y.

MATERIAL FOR FILLING MATTRESSES.

SPECIFICATION forming part of Letters Patent No. 312,036, dated February 10, 1885.

Application filed May 12, 1884. (No specimens.)

To all whom it may concern:

Be it known that I, RICKASON STILWELL, of the city, county, and State of New York, have invented an Improvement in Materials 5 for Filling Mattresses, Pillows, Beds, and for other like purposes, of which the following is a specification.

This invention comprises a new article of manufacture or composition of matter intended 10 for filling mattresses, pillows, beds, and for other like purposes—as, for example, the topping (so called) of mattresses—the said article combining to an unusual and most advantageous degree the advantages of cheapness, durability, and elasticity. The said 15 new article of manufacture or composition of matter is composed of shoddy and a fiber commonly known in the trade as “cat’s-tail,” and which is obtained from the spikes of the common “cat’s-tail flag”, so termed, the combination 20 of these substances producing an article having the useful characteristics hereinbefore indicated. In the production of the said article of manufacture or composition of matter 25 I mingle the two materials—that is to say, the shoddy and the cat’s-tail fiber—in any suitable proportions, taking care that the one shall be interspersed throughout the other with substantial uniformity—that is to say, 30 in such manner that the extremely light character of the cat’s-tail fiber shall be counterbalanced to the requisite degree by the extremely heavy character of the shoddy. This may be done by any suitable means—as, for example, by passing the two substances between a toothed revolving cylinder and a fixed 35 toothed concave suitably adjusted thereto, such apparatus being similar to that ordinarily used in separating or loosening curled hair. The materials may also be mingled by the use of an ordinary carding apparatus.

It is to be understood that the cat’s-tail fiber by itself is extremely light and elastic, but of a comparatively unsubstantial character as

concerns its resistance to pressure, and that 45 shoddy is, on the other hand, extremely heavy, deficient in elasticity, and liable to closely mat or pack into a dense layer unfitted for any except the inferior classes of work known in the trade.

By commingling the two materials as herein set forth the dense or heavy character of the shoddy counteracts the extreme lightness of the cat’s-tail fiber, while, on the other hand, the light and elastic character of the cat’s-tail fiber counteracts the tendency of the shoddy to mat together, so that the conjunction of the two materials as aforesaid provides a new material especially fitted for the purpose of filling up beds, mattresses, pillows, and the like, possessing advantages not existing in either of the component parts by itself, and devoid of the defects and drawbacks in practical use experienced with the component parts when used separately, the said material being, 60 furthermore, capable of production at a much less price than any other filling for mattresses, pillows, beds, and the like possessed of equivalent elasticity and durability heretofore known in the trade.

In the manufacture of my improved article of manufacture or composition of matter as aforesaid the proportions of the two component parts may be varied within very wide limits; but ordinarily the proportion of one 75 pound of shoddy to two pounds of the cat’s-tail fiber will be found productive of the best results for the purpose of filling for beds, mattresses, pillows, and the like.

What I claim as my invention is—

A new article of manufacture or composition of matter composed of intermingled shoddy and cat’s-tail fiber, substantially as and for the purpose herein set forth.

RICKASON STILWELL.
